UNITED STATES PATENT OFFICE.

HIRAM A. BACKUS, OF EVANS, NEW YORK.

LEVER.

SPECIFICATION forming part of Letters Patent No. 679,873, dated August 6, 1901.

Application filed September 12, 1900. Serial No. 29,803. (No model.)

To all whom it may concern:

Be it known that I, HIRAM A. BACKUS, a citizen of the United States of America, residing at Evans, in the county of Erie and State 5 of New York, have invented certain new and useful Improvements in Levers, of which the following is a specification.

My invention relates to an improvement in power-exerting devices, and more particularly 10 to that class of devices whereby a maximum weight or resistance may be overcome by a minimum expenditure of power.

Hitherto it has been the general custom to employ a fulcrum when attempting to move 15 heavy weights—as, for instance, buildings—or to extract stumps from the ground, and by using this fulcrum a very appreciable amount of force is lost during the operation, which force or power, if saved, would materially aid 20 and assist in the accomplishment of the purpose in view. In my improved lever I do away with the fulcrum affixed to the ground formerly used, thereby utilizing all the power 25 formerly lost, and by means of my construction causing it to assist in attaining the object in view.

My invention consists in a power-exerting device comprising a flexible device extending between an object to be moved and any suitable 30 staying power, in combination with a lever provided with a plurality of pairs of gripping devices located at different points on the lever, which gripping devices are adapted to engage the flexible means and when the 35 lever is operated to advance the movable object.

It further consists of certain other novel details of construction and combination of parts, such as will be more fully described 40 hereinafter and particularly pointed out in the claims.

In the accompanying drawings, Figure 1 is a perspective plan view of my device, showing it in readiness for operation. Fig. 2 45 shows the lever at the end of its throw in one direction. Figs. 3 and 4 are slight modifications, and Fig. 5 is a detail view of the traction-wheel.

A represents the lever, which may be of any 50 suitable shape. Its length, of course, may vary with the amount of space in which it is to be used and the weight to be moved or

resistance to be overcome. Near one end oppositely-extending chains 1 2 are secured by pivoted double-looped shackles and having grappling-hooks 3 4 at their outer or free ends. A similar arrangement of chains 5 6 and hooks 7 8 is secured to the lever at a little distance nearer the opposite or free end of the lever. The distance existing between 60 these two sets of chains may vary, as it is obvious that a longer swing can be had when the sets of chains are farther apart and a greater amount of power exerted than when the sets of chains are nearer each other, 65 when a shorter swing at the expense of less power is obtainable. Near the opposite or free end of the lever a standard 9, provided with a wheel 10 at its lower end, may be affixed to the under side of the lever in any suitable 70 manner to support the weight of the lever. This is only necessary when the length of the lever is such as to render its support from the ground difficult without the aid of a standard. A clevis-hook 11 is also secured to the end of 75 this lever in order to utilize horse-power, if desired.

B indicates a chain or cable, the two free ends of which are attached to the object to be moved, thus doubling the chain, which is 80 rove through a pulley 14 or similar device fastened to a stationary object, such as a pile driven into the ground. The two strands of the chain are indicated by the numerals 12 13. 85

As seen in the drawings, the lever is placed in such a manner that the hooks on both sets of short chains may be attached to strand 12 of the chain B in an alternate manner—that is, one of the hooks 4 engages the chain B 90 when the opposite hook 7 is engaged, and vice versa. When the hooks are coupled to the chain, the lever is swung to the right, whereupon the chain B will be tightened and will transmit an immense power upon the object 95 to be moved, not only directly through the strand 12 between hook 4 and the object to be moved, but also a pull will be transmitted along the strand 12 between hook 7 and the pulley 14, which is exerted upon the 100 object through strand 13. Thus the object is subjected to a double pull or power exerted upon it by the lever through each strand of the chain B, and the object will be drawn

forward a length equal to that traveled by the hooks 4 and 7. At the end of one swing the hooks 3 and 8 will engage the strand 12 for a swing in the reverse direction, after the completion of which the hooks 4 and 7 are released from their first position and made to engage the strands at points farther along, when a repetition of their former movement results.

10 Fig. 3 and 4 illustrate modifications of my device. Fig. 3 shows the wire cable or chain B rove through two pulleys, one of which is secured to a stationary object and the other to the object which it is desired to move. 15 The free ends of the cables are grasped by the hooks which operate as previously described. In Fig. 4 is shown a device whereby hand-power may be utilized. In this construction there is but a single chain B, connected at one of its ends to the object to be moved and its opposite end secured to a stationary object. The lever is of any convenient length and has the four short chains provided with hooks at their outer or free ends. 20 These chains, however, are each arranged at an equal or approximately equal distance from the central point of the lever, which extends upon either side of the chain and has places for the hands at each of its extreme 25 ends. The hooks engage chain B, as before described. One man or more on either side may then operate the device, as hereinbefore described.

By means of my invention I can move the 30 heaviest weights or overcome the largest resistance by merely increasing the number of pulleys or lengthening the lever, or both. I do away with the use of a stationary fulcrum, now in general use, and can adapt my improvement to use in crowded places as well as where I can have plenty of space in which to swing the lever.

The device operates entirely independently of any hitch or support, and my device may 40 be applied to any sort of work wherein heavy weights are to be moved or resistances overcome, and yet it is simple, cheap, and durable. It doubles the usual leverage exerted by a common lever.

50 The saving of power by omitting the use of a stationary fulcrum is one of the main objects of my construction, and the power which has heretofore been lost by employing a stationary fulcrum is in my device reversed 55 back and acts upon the building, weight, or resistance through the two strands of chain, one from the lever to said weight and the other to the weight or resistance past the lever, through the pulley, and back to the short 60 chains and hooks. In fact, it is a device without an equal in power, retaining its position and sustaining its draft upon an incline. It is adapted for moving light or heavy weights by using either a small hand-lever or an extra- 65 heavy horse-lever twenty-five or thirty feet long with extra wire cables, having chains shackled to their ends and iron ball-bearing

sheaves. Its power is unlimited up to fifty-thousand-horse power.

The invention can be applied in any convenient place. It may be used to warp a vessel into its dock with a twenty-foot hand-lever and a shackle at the stern or side of the vessel, so that the lever can swing on the deck, or it would prove of inestimable value in a 75 railway accident by providing a simple means with which to move the heavy wreckage.

It is evident that slight changes other than those herein noted might be made in the form and arrangement of the several parts described without departing from the spirit and scope of my invention, and hence I do not wish to limit myself to the exact construction herein set forth; but,

Having thus described my invention, what 85 I claim as new, and desire to secure by Letters Patent, is as follows:

1. In a power-exerting device, the combination with a flexible means extending between an object to be moved and any suitable staying power, of a lever, a plurality of pairs of gripping devices situated at different points on the lever, the gripping devices engaging the flexible means at opposite points whereby when the lever is swung, to simultaneously exert a tension on the flexible means in opposite directions.

2. A lever provided with a plurality of sets of chains, the individual members of the sets extending in opposite directions from one another; a main chain extending between an object to be moved and any suitable staying power, the alternate chains on the lever engaging the main chain whereby when the lever is operated, to slacken that portion of the main chain held between them, and cause the movable object to advance by exerting a pulling force thereon.

3. A lever provided with a plurality of double-looped shackles pivoted thereon, a 110 plurality of pairs of chains oppositely mounted on the lever by means of said double-looped shackles whereby the chains are capable of a lateral swing as the lever is operated, a main chain extending between the object 115 to be moved and any suitable staying power, the alternate chains on opposite sides of the lever engaging the main chain whereby to advance the movable object step by step, when the lever is operated, by exerting a pulling force thereon.

4. The combination with a lever provided with a plurality of pairs of gripping devices secured thereto at different points, of a flexible connection extending between an object 125 to be moved and any suitable staying power, the gripping devices alternately engaging the flexible connection whereby, when the lever is operated to cause the advance of the object to be moved.

5. The combination with a lever provided with two pairs of short chains pivotally attached thereto, the individual members of each pair extending oppositely from one an-

other and parallel with the corresponding individual member of the other pair of chains, of a main chain extending between an object to be moved and any suitable staying power, 5 the alternate individual members of each pair of lever-chains removably attached to the main chain, whereby to advance the object to be moved step by step.

6. A lever provided with a plurality of pairs 10 of short chains at or near one end thereof, the chains extending oppositely to one another and at approximately right angles to the lever, a main chain extending between the object to be moved and any suitable staying 15 power, hooks on the lever-chains removably engaging the main chain, the alternate chains of each pair engaging the main chain, whereby to slacken that portion of the main chain held between them, to advance the object, 20 when the lever is operated, and a standard provided with a traction-wheel, the standard secured to the lever for its support.

7. A lever provided with a plurality of pairs 25 of gripping devices extending oppositely to one another, a flexible means extending between an object to be moved and any suitable staying power, the diagonally-opposed gripping devices alternately engaging the flexible means whereby to cause it to exert a 30 pulling force on the object to be moved when the lever is operated, the device being so constructed that it will retain its position whenever the operating force is removed, thus preventing the movable object from returning to 35 its original position.

8. In a power-exerting device, the combination with a flexible means extending between the object to be moved and any suitable staying device, of a lever, a plurality of pairs of 40 gripping devices situated at different points on the lever, these gripping devices adapted to engage the flexible means at opposite points whereby, when the lever is operated, to simultaneously exert a pulling force upon the 45 flexible means in opposite directions.

9. A lever provided with a plurality of pairs of gripping devices, in combination with a

flexible connection extending between an object to be moved and any suitable staying power, one member of each pair of gripping 50 devices adapted to engage the flexible connection whereby, when the lever is operated, to cause a tension or pulling force to be exerted on the flexible connection and thereby upon the object to be moved, the device being so arranged that it will retain its position at the end of a stroke thus preventing the movable object from returning to its original position.

10. In a power-exerting device, the combination with a main cable extending between an object to be moved and any suitable staying power, of a lever provided with a plurality of pairs of gripping devices extending in opposite directions from one another, and 65 adapted to removably clutch the main cable, whereby a pulling force is exerted upon the object to be moved, when the lever is operated.

11. In a power-exerting device, the combination with a cable extending between an object to be moved and a suitable staying power, of a lever provided with pairs of gripping devices located oppositely to one another and adapted to removably clutch and hold the 75 main cable whereby, when the lever is operated, to exert a pulling force on the object to be moved.

12. In a power-exerting device, the combination with a lever provided with a plurality 80 of pairs of gripping devices, of a flexible device connecting the object to be moved with some suitable staying power, the diagonally-disposed member of each pair of gripping devices adapted to alternately engage the flexible device whereby, when the lever is operated, to advance the object to be moved.

In testimony whereof I have signed my name to this specification in the presence of two subscribing witnesses.
